UNITED STATES PATENT OFFICE.

EDWARD J. MANNING, OF BAYONNE, NEW JERSEY, ASSIGNOR TO THE
WAGNER TYPEWRITER COMPANY, OF NEW YORK, N. Y.

DESIGN FOR A RIBBON-SPOOL FOR TYPE-WRITING MACHINES.

SPECIFICATION forming part of Design No. 31,675, dated October 17, 1899.

Application filed September 26, 1899. Serial No. 731,772. Term of patent 14 years.

To all whom it may concern:

Be it known that I, EDWARD J. MANNING, a citizen of the United States, residing in Bayonne, Hudson county, State of New Jersey, have invented and produced a new and original Design for a Ribbon-Spool for Type-Writing Machines, of which the following is a specification.

The characteristic features of my design consist in a ribbon-spool for type-writing machines, which spool has a hub, on the opposite ends of which are disk-like flanges, each of which flanges is apertured to present a wheel-like appearance.

In the drawings, Figure 1 represents a face view of a ribbon-spool made in accordance with my design. Fig. 2 is an edge view of the same.

The ribbon-spool has a cylindrical centrally-apertured hub *a*, to each end of which is secured a disk-like flange *b*. Each of these flanges is apertured, as indicated at *c*, to form radiating spokes *d* and a rim *e*. Each of the flanges is shown corrugated, as indicated at *f g*, and the hub has a depression *h* therein to one side of the central aperture *i*.

What I claim is—

The ribbon-spool for type-writing machines substantially as herein shown and described.

EDWARD J. MANNING.
